US00D820267S

(12) **United States Design Patent** (10) **Patent No.:** **US D820,267 S**
(45) **Date of Patent:** **** Jun. 12, 2018**

(54) **BENDABLE DEVICE CASE**

(71) Applicant: **Intel Corporation**, Santa Clara, CA (US)

(72) Inventors: **David M. Collins**, San Francisco, CA (US); **Douglas Satzger**, Santa Clara, CA (US); **Michael A. Hyde**, Santa Clara, CA (US)

(73) Assignee: **Intel Corporation**, Santa Clara, CA (US)

(**) Term: **15 Years**

(21) Appl. No.: **29/505,644**

(22) Filed: **Dec. 24, 2015**

(51) LOC (11) Cl. **14-02**

(52) U.S. Cl.

USPC **D14/440**

(58) **Field of Classification Search**

USPC D14/250, 440, 447; 206/45.23, 320, 206/45.2; 361/679.55; 294/25; 224/218; D7/554.3

CPC G06F 1/1628; G06F 1/1613; G06F 1/1626; A47B 23/044

(57) **CLAIM**

The ornamental design for a bendable device case, as shown and described.

DESCRIPTION

FIG. 1 is a front view of a bendable device case; FIG. 2 is a back view of the bendable device case from FIG. 1; FIG. 3 is a top view of the bendable device case from FIG. 1; FIG. 4 is a bottom view of the bendable device case from FIG. 1; FIG. 5 is a left view of the bendable device case from FIG. 1; FIG. 6 is a right view of the bendable device case from FIG. 1; and FIG. 7 is a top left perspective view of the bendable device case from FIG. 1. FIG. 8 is a top left perspective view of a bendable device case with a long edge raised. FIG. 9 is a left perspective view of a bendable device case in a first portrait mode with a short edge raised; and, FIG. 10 is a top left perspective view of the bendable device case housing a computing device with a long edge raised. The broken lines depict environment and form no part of the claim.

1 Claim, 10 Drawing Sheets
